UNITED STATES PATENT OFFICE.

OSCAR G. ZIEGLER, OF HALETHORPE, MARYLAND, ASSIGNOR TO A. HOEN & COMPANY,
OF BALTIMORE, MARYLAND, A FIRM.

KNOCKDOWN DISPLAY-RACK.

1,301,797.

Specification of Letters Patent. Patented Apr. 22, 1919.

Application filed January 21, 1919. Serial No. 272,259.

To all whom it may concern:

Be it known that I, OSCAR G. ZIEGLER, citizen of the United States, residing at Halethorpe, in the county of Baltimore, and 5 State of Maryland, have invented certain new and useful Improvements in Knock-down Display-Racks, of which the following is a specification.

This invention relates to improvements in 10 knock-down display racks.

The objects of the invention are to provide an improved construction of display rack that may be readily assembled or taken apart; that may be constructed of heavy 15 card-board but when set up be of sufficient rigidity to hold an article of considerable weight,—such as an automobile tire; which will display the article in an upright position, and provide ample surface for the 20 display of advertising matter and which when taken apart may be packed in a flat condition and shipped if desired, in a crate with a single tire.

The invention is illustrated in the accompanying drawing, in which,—

Figure 1, shows the improved device in perspective.

Fig. 2, illustrates the same in side view.

Fig. 3, shows the assembled rack in top 30 plan, and

Fig. 4 illustrates, in perspective, the separated parts of the rack in relative positions one with respect to another for assembly to show how the several slotted edges of the 35 parts interlock one with the other.

Referring to the drawing, the numerals 5 and 6 designate two main supports each having a rear upright portion 7, and a forwardly-extending base portion 8, at its lower end. The upright portion of each main support has a front edge 9, and the forwardly-extending base of each of said main supports is provided in its upper edge 40 with a slot 10, immediately in front of said front edge, whereby said front edge 9, and the slot 10, both project down below the uppermost edge 11, of said extending base portion, as clearly seen in Fig. 4, of the drawing.

50 At the rear, each main support is provided with a slot 12, which extends forwardly from the rear edge 13, and toward the front edge 9, and by preference, these slots 12, are inclined downwardly so that 55 their forward ends are lower than their rear

ends, for a purpose which will presently be explained.

The forwardly-extending base portion of each main support also has a slot 14, extending upwardly from the bottom or base edge 15, which latter slot is preferably parallel with the slot 10, and also with the front edge 9, of the upright portion.

The two main supports are to be sustained in an upright position on the base edges 15, 65 but spaced with respect to each other, and the means for effecting this spacing will now be explained.

A front bar 16, has two spaced apart notches 17, extending downwardly from its upper edge 18, and the unnotched space 20, between the lower ends of these notches and the bottom edge 21 of the bar is equal in depth to the depth of the slots 14, in the base portion of the main 70 supports, so that the notches 17, and the slots 14, may be brought into register until the inner ends of the two abut, whereupon the bottom edge 21, of the front bar 16, and the bottom or base edge 15, of the main supports will become flush, as shown in Fig. 2, 80 of the drawing. The engagement, therefore of the downwardly-extending notches of the front plate 16, with the upwardly-extending slots 14, of the main supports not only locks 85 the supports to the bar but also effects a spaced-apart front locking of the two supports with respect to each other so that neither longitudinal nor lateral movement 90 can take place between the locked-together parts.

At the rear the two main supports are held in a spaced-apart locked condition by a rear spacer bar 22, which latter also has spaced apart notches 23, which extend rearwardly from its forward edge 24. These notches 23 are of such depth that when they are brought into register and straddled with the slots 12, in the upright portions 7, of the main supports, the rear edge 25, of 100 the rear spacer bar will be flush with the rear edge 13, of the main supports, and the front edge 24, of said rear spacer bar will be flush with the front edge 9, of said main supports. When this spacer bar 22, is engaged with the two spaced main supports it will have an inclined position with respect to the latter as shown in Fig. 2, and danger of accidental rearward displacement of said rear bar is avoided.

2
A partition plate 26, is provided between the front spacer plate 16, and the rear spacer bar 22, and this partition plate has a lower straight bottom edge 27; with spaced-apart notches 28, extending upwardly from said bottom edge. This partition plate has position directly in front of the edges 9, of the uprights 5 and 6, and the notches in the lower or bottom edge straddle the slots 10, in the projecting portions 8, of the two main supports and thereby provide an intermediate cross-wise locking of the two main supports in addition to retaining the partition in place. The rear side of the partition plate seats against the edges 9, at the front of the uprights of the main supports, and is therefore braced so as to withstand pressure that may be applied to its front side.

In outline the partition plate may vary, but in the present instance I have made its upper portion of a circular outline because I have designed the form shown particularly as a rack for sustaining and displaying automobile tires. For this same reason I provide the upper edge of each extended base portion 8, with a concavity 29, which latter is located between the front spacer plate 16, and the partition plate 26, so that the circumferential surface of a circular tire may seat in the two spaced-apart concavities while the upper portion of the tire may incline slightly and rest against the partition plate, as shown by broken lines in Fig. 2, of the drawing.

35 From the foregoing explanations it will be seen that the rack is formed from a series of flat plates, thick card-board being the preferred material, which are notched and slotted so as to fit one into another whereby 40 to firmly lock the several plates together and that the same may be readily assembled or taken apart. It will also be seen that when the plates are separated they may readily be laid one upon another and placed in a 45 crate with a single sample tire and shipped to a place where the tire is to be displayed.

In practice, the central circular portion of the partition plate 26, affords ample space for advertising matter as does also the front 50 flat face of the front plate 16.

What I claim is,—

1. In a display rack the combination with two separate upright supports, of a detachable front bar connecting said supports at 55 the lower front portion of the latter and holding the same spaced apart; a separate rear plate detachably connecting the upper

portion of said supports at the rear, and a detachable upright partition plate sustained by the supports between the lower front bar 60 and the upper rear plate.

2. In a display rack the combination with two separable upright supports each having a forward extension at its lower front side, of a detachable spacer bar extending between and connecting the forward extensions of said supports to lock the same in spaced relation; a separate and detachable rear plate in a plane above the forward extensions and extending between and detachably connecting the separable upright supports, and a plate secured to the said forward extensions and extending upwardly in front of the detachable rear plate.

3. In a display rack the combination with two upright supports each having a forward extension at its lower end and each extension having a slot extending downwardly from its upper edge and also having a slot extending upwardly from its bottom edge 80 and in front of the downwardly-extending slot, of a spacer bar having spaced-apart slots which open at the upper edge said spacer-bar slots and the upwardly-extending front slots in the forward extension 85 being straddled whereby to hold the supports in spaced relation; detachable means connecting the upright supports to space the latter at the rear of the forward extensions and a plate engaging the downwardly-extending slots in the forward extensions said plate projecting upwardly in front of the upright supports.

4. In a display rack the combination with two separate upright supports each having a forward extension with a concavity extending from front to rear in its upper edge and with a slot in the extension that extends down from said upper edge and at the rear of the edge-concavity, of an upright plate 100 having bottom-edge notches which register with and straddle the notches in said forward extensions of the two upright supports and said plate extending upwardly from the said extensions and in front of the upright 105 supports; a detachable spacer bar connecting the two forward extensions in front of the edge concavities and a detachable rear spacer plate connecting the two supports at the rear of the upright plate and in a plane 110 above the said extensions.

In testimony whereof I affix my signature.

OSCAR G. ZIEGLER.
